UNITED STATES PATENT OFFICE.

JOHN J. PETERS, OF OELWEIN, IOWA, ASSIGNOR OF ONE-THIRD TO BEN J. McDONNELL,
OF WATERLOO, IOWA.

VACUUM CLEANER.

Application filed October 4, 1923. Serial No. 666,528.

To all whom it may concern:

Be it known that I, JOHN J. PETERS, a citizen of the United States of America, and a resident of Oelwein, Fayette County, 5 Iowa, have invented certain new and useful Improvements in Vacuum Cleaners, of which the following is a specification.

My invention relates to improvements in vacuum cleaners, and the object of my improvement is to improve the manner of collecting and filtering within the apparatus.

These objects I have accomplished by the means which are hereinafter described 15 and claimed and which are illustrated in the accompanying drawings, it being understood that changes in the precise embodiment of invention herein disclosed can be made within the scope of what is claimed 20 without departing from the spirit of the invention.

In said drawings, Fig. 1 is a vertical central section of the dust collector and filtering device of the apparatus, and Fig. 2 is 25 a side elevation of the same.

The dust collecting receptacle 1 is closed at the top but has a curvate receiving tube 2 integral with its top and upon which is terminally removably mounted the delivery 30 end of a flexible hose 10.

The receptacle 1 has a port 15 a short distance below its top in communication with a pipe 18 by way of a stop-cock 17 having a manually operable handle 16, the 35 pipe 18 being tapped into the wall 19 of some apparatus for exhausting air from said receptacle 1, such as the upper part of the inlet manifold of an internal combustion engine of the type employed on 40 motor vehicles.

The receptacle 1 is preferably constructed with both upper and lower sections 1 and 3 respectively, the lower section or member being of cupped shape to 45 be mounted upon the lower part of the upper section or member 1 and secured removably and adjustably thereon by a threaded connection 5. However, any other kind of securing means may be employed in this relation as desired.

The receptacle may be supported adjacent to the air-exhausting means in any desired manner, such as being secured removably on a cowl wall of a motor vehicle. The numeral 27 denotes a like pair

of horizontal bracket-arms, reversed with respect to each other, and having terminal feet 28 which may be secured to a cowl wall by means of screws 29. A substantially horizontal flat ring 20 has at opposite sides bendings providing inwardly socketed seats 24 to lockingly receive squared nuts 26, the latter mounted on the inwardly disposed threaded ends of short bolts 25 which traverse registering holes in the arms 27 and the ring to serve as supporting pintles for the ring which is positioned between the arms 27 tiltably. The ring 20 is a split-ring with outturned parallel ends 21 connected together adjustingly by means of a bolt 22 and wing-nut 23. Referring to said Fig. 2, the ring 20 has at opposite sides integral hangers or depending projections 32 provided with vertical slots 34. The arms 27 have integral depending projections or plate members 31 which overlie the other projections 32 and have transverse curvate slots 33 which cross the said vertical slots 34, the slots 33 being arcuate and concentric with the pintles 25. Short 80 bolts 35 traverse the crossed slots 33 and 34, and are provided with nuts 36, whereby the projections 32 may be tilted together with the ring 20 and the receptacle 1 when clamped within the ring, to properly maintain the receptacle in a vertical position, as the pipe 18 is not relied upon as a supporting means for the receptacle.

Within the receptacle 1 is mounted a hollow inverted cone 4 with open upper end 90 which is shaped to closely fit against the abutting inner wall of the receptacle upper member 1, and this cone structure 4 may be integral with or fixed to the top center of the bottom of the lower cupped member 3, 95 or may be separable therefrom as desired. The lower or apical end of the cone may have one or more openings 6 next to the bottom of the member 3. Any suitable straining material of a porous nature such as sponge 7 may be used to cross the ports 6, whether within the cone as shown, or without the cone, so as to be displaceable for cleaning. Water may be placed within the cupped member 3 as shown to be at a 100 height sufficient to be above the ports 6 and immerse the porous material 7 in whole or in part, so that the porosities thereof may fill with water by capillary attraction or mere submergence.

- The numeral 9 denotes a conical dust-bag, preferably made of some reticulated textile, or other substance having many minute apertures thereover. The upper wider end of this bag or sack 9 is mounted around a ring 8 held between the upper edge of the cone 4 and the top of the part 1 at its interior angle, so that the material 9 surrounding the ring serves as a packing therefor and making a closed connection. The port 2 opens into the upper open end of the sack 9. The sack is spaced apart from the inner wall of the cone 4 to not contact therewith.
- 15 When the air-exhausting apparatus is in operation, whether by the means previously described or otherwise, the stop-cock 17 being opened, the air in the receptacle 1—2 is exhausted in turn exhausting the air in 20 the tube 10 and nozzle 12.

Dust laden air being drawn into the nozzle and thence into the receptacle 1, passes downwardly and is separated from nearly all of its dust content by the reticulated sack 9. Whatever finer dust traverses the sack downwardly is drawn into the sponge strainer 7, and the cleansed air passes the ports 6 and then upwardly to the port 15 to discharge it into the pipe 18 and 25 inlet manifold of the engine, or into other air-exhausting apparatus.

By detaching the member 3 from the receptacle member 1, the water in the former which may have been somewhat defiled by 30 finer dust, may be emptied, and the sponge 7 removed for cleansing, or water forced through the sponge while in the cone to wash it out. The ring 8 and sack may also be removed to empty out its contents.

Having described my invention, what

I claim as new, and desire to secure by Letters Patent, is:

1. In combination, a closed dust-collecting receptacle having both inlet- and outlet-ports and composed of a downwardly 45 cupped upper member and an upwardly cupped lower member removably mounted thereon, said lower member having a hollow inverted cone rising from its bottom into the upper member with the upper edge 50 of the cone closed against the interior wall of the latter, said cone having a port in its lower end, a porous filtering body closing said port, a ring secured in the upper end of the upper member around the first 55 mentioned port, and a reticulated dust collector sack mounted on said ring to depend within the cone in spaced relation to the latter.

2. In combination, a closed dust-collecting receptacle having both inlet- and outlet-ports, a porous sack inclosing the inlet-port and depending into the receptacle, an imperforate hollow body within and spaced 60 from the receptacle surrounding said sack to seal the upper end of the sack between the inlet-port and the interspace of the said body and receptacle, said body having an open lower end in communication with said interspace, and a porous strainer-body 65 positioned across said open lower end for immersion in a liquid placed in said receptacle to cover the said open lower end only, said outlet-port being located in said receptacle above the level of said open lower end and said liquid.

Signed at Waterloo, Iowa, this 8th day of Sept., 1923.

JOHN J. PETERS.
